UNITED STATES PATENT OFFICE.

WILLIAM ROBERT HONEYBALL, OF PASADENA, CALIFORNIA.

SIGNAL.

1,218,864.

Specification of Letters Patent. Patented Mar. 13, 1917.

Application filed March 20, 1914, Serial No. 825,962. Renewed July 25, 1916. Serial No. 111,281.

To all whom it may concern:

Be it known that I, WILLIAM ROBERT HONEYBALL, a citizen of the United States, residing at Pasadena, in the county of Los Angeles and State of California, have invented certain new and useful Improvements in Signals, of which the following is a specification.

This invention relates to improvements in signals, and more particularly to electrical signals. The leading feature of my invention is to provide improved means of signaling adapted for use on self-propelled vehicles, whereby the right of road may be obtained for the occupants of one automobile in preference to another.

One of the objects of my invention is to provide a simple, efficient and inexpensive means of electrical signaling where a plurality of signs are adapted to be brought opposite a sight opening formed in a casing or sign box carried at the rear of the automobile, as is requisite, the number plate being also carried by this sign box.

25 A further object of this invention is to provide novel signal mechanism whereby the chauffeur may manually control the operation of a particular signal to be conveyed from the rear of the automobile, such as 30 "left", "right", etc. The principle involved in my signal mechanism is embodied in a drum formed of a circumferentially extending series of signs actuated electrically so that any one of said signs is adapted to be 35 exposed separately through a sight opening formed in a sign box, said drum being designed to move at varying intervals of duration and being automatically stopped so that one of the signs may be exposed.

40 With the above and other objects in view my invention consists in the combination, arrangement and details of construction disclosed in the drawings and specification, and then more particularly pointed out in the appended claim.

In the drawings wherein similar reference characters designate similar parts:

Figure 1 is a front elevation of my invention;

50 Fig. 2 is a cross sectional view thereof, taken on the line 2-2 of Fig. 4;

Fig. 3 is a cross sectional view of my invention taken on the line 3-3 of Fig. 4;

55 Fig. 4 is a longitudinal sectional elevation of my invention giving a top plan view of the inside of the sign box;

Fig. 5 is a diagrammatic view of a means

for causing the stencil to move step by step; and

Fig. 6 is a diagrammatic view of the electro-magnets designed to control a given number of signs or signals.

Reference being made to the drawings, there is disclosed a sign box or casing of any suitable construction designated 1. 65 This sign box is provided at 2 with a suitable sight opening through which will be exposed, one at a time, a series of characters or signs 3, adapted to convey any desired signal, these signs being circumferentially carried by or upon a rotatable drum 4, the latter being fixed upon a shaft 5 extending longitudinally within said casing. The usual number plate 6 will depend, preferably, from the casing or box 1, 75 extending the length thereof. A partition 7 may divide the casing into two compartments 8 and 9, the latter being designed to hold a lamp 10 which will cast red beams across to the bull's eye lens 11 mounted at 80 the forward side of the casing, a red light being required by law. Another lamp 12 will be secured in the compartment 8 so as to shed its light upon the translucent drum 4, thereby enabling any of a series of signs 85 carried by said drum to be well illuminated at night. Both lamps 10 and 12 may be included in one circuit, the description of which is dispensed with, as it relates to no part of my invention. 90

It will be seen that one end of the translucent drum 4 is open, and in this end projects the lamp 12. Fixed upon one end of the shaft 5 is a cog wheel 13 and meshing therewith is a toothed segment 14 fixed upon 95 a lever 15 fulcrumed upon a pivot carried by a bracket 17, the latter being secured in insulated relation upon a solenoid or electro-magnet 18 secured upon the angular lug 19 formed upon a longitudinally extending supporting frame or bar 20. A second supporting frame or bar 21 also extends longitudinally, together with the bar 20 in said drum 4, being preferably disposed parallel to said bar 20. A link 22 pivotally connects the 100 lever 15 intermediate its ends to the solenoid core 23 which, under the well known laws of electro-magnetism, will, when the electro-magnet 24 is energized, move or slide inwardly of the magnet, being attracted 110 thereby.

I will now describe the automatic mechanism for assuring that the drum will be rotated step by step in a constant ratio of

increase in its duration or interval of movement. A series of disks 25, four in number where four signs are to be separately displayed, are fixed in spaced relation upon the 5 shafts 5, each of these disks 25 being provided with a single ratchet tooth 26. The four ratchet teeth 26 carried by the disk all occupy different positions relative to each other upon the circumferences of the disks, 10 being positioned at intervals of a quarter circle as is clearly shown in Fig. 5. Four magnet controlled pawls 27 are adapted to engage with the four ratchet teeth in such a way as to engage with the substantially plane 15 surface 28 formed upon each disk. Inasmuch as the pawl-actuated means is similar for each pawl it will suffice to describe but one, it being understood, however, that four actual magnets 29, 30, 31 and 32 will be 20 secured in two pairs, each upon one of the bars 20 and 21, as illustrated in Fig. 4. A solenoid core 33 will be slidably mounted within each of said electro-magnets 29, 30, 31 and 32, and secured to each one of said 25 electro-magnets is a bracket arm 34 similar to the bracket arm 17, this bracket arm as well as that numbered 17, having a contractile spring 35 secured to it, the opposite end of one of these springs being secured, in one 30 case, to the lever 15, and in the other case, to the pawl 27, which is fulcrumed at its lower end as at 36 to said bracket arm 34.

A suitable switch plate 37 will be located 35 so as to be readily accessible to the operator or chauffeur of the car. Four contact buttons 38 are arranged concentrically upon said plate near its periphery, and a pivot 39 is mounted directly on the center of this plate 37 upon which is fulcrumed one end 40 of the lever or switch 40 which carries the handle 41 by means of which said lever may be turned so as to abut any of said contact buttons 38. The numeral 42 designates a source of energy, such as a battery, and a 45 wire 43 leads from one side of the battery 42 to the collector pivot 39. Leading from the opposite side of the battery is a wire 44 to the coil of electro-magnets 18 and this wire 44 is connected in series to each of the 50 remaining electro-magnets 29, 30, 31 and 32, the latter being connected to the first mentioned side of the battery by means of the respective wires 45, 46, 47 and 48, which are connected to the contact buttons 38.

55 The mode of operation of this invention will be explained as follows: The signs 3 will be separated an equal distance upon the drum 4, which distance is equal to the spacing of the ratchet teeth 26. The operator 60 grasps the lever or switch 46 and brings it into contact with either of the buttons 38. The circuit will then be closed both to electro-magnet 18 and to the particular electro-

magnet of the series 29, 30, 31 and 32 intended to be energized so that both electro-magnets will be energized at the same time. This will cause the respective solenoid cores 23 and 33 to slide or move inwardly of said magnets, and when this occurs, in one case, the link 22 will draw the lever 15 downwardly so that the toothed segment will rotate pinion or cog wheel 13, and shaft 5 will turn therewith, but as the disks rotate with said shaft, as soon as the link 46 carried by each of the pawl-operating electro-magnets is moved inwardly against the tension of the spring 35 adapted to normally hold the pawl 27 out of range of the disk in question, the pawl will be pulled down so as to have its free end directly opposed to the ratchet tooth 26 formed upon the disk, thereby projecting in to the path of movement of said tooth and preventing the rotation of the disk, shaft 5 and drum 4 and thereupon a given sign will be exposed opposite the sight opening 2. In the same way any of the other pawls can be operated, and then another and different sign will be exposed through said sight opening 2. When the lever 15 has been pulled down its spring 35 will be put under tension and, therefore, as soon as the switch 40 is moved to a neutral position, as shown in Fig. 6, the magnet will be deenergized and the spring 35 will recoil, allowing the segment 14 and pawl 27 to be restored to normal position ready for another operation.

Modifications within the scope of the claim may be resorted to in practice without departing in principle from the details of construction disclosed.

Having thus described my invention, I claim:

In combination, a casing provided with a sight opening therein, an electric lamp arranged interiorly of said casing, a transparent drum having one end closed and rigidly secured to said shaft and its opposite end open and arranged around said lamp, electro-responsive means for rotating said shaft, two pairs of magnets arranged on opposite sides and co-operating with said shaft for allowing the latter to make a complete or partial revolution, control circuits for said magnets, and a supporting bar for each of said pairs of magnets, and arranged below the sight opening, said bar passing through the open end of the drum and secured to the casing.

In testimony whereof I affix my signature in presence of two witnesses.

WILLIAM ROBERT HONEYBALL.
